Inventor:

Thos J. McGeary

United States Patent Office.

THOMAS J. McGEARY, OF NEWARK, NEW JERSEY.

Letters Patent No. 96,022, dated October 19, 1869.

IMPROVED PLASTERERS' HAWK.

The Schedule referred to in these Letters Patent and making part of the same.

To all whom it may concern:

Be it known that I, THOMAS J. McGEARY, of Newark, in the county of Essex, and State of New Jersey, have invented a new and useful Improvement in Plasterers' Hawks; and I do hereby declare that the following is a full, clear, and exact description thereof, sufficient to enable others skilled in the art to which my invention appertains, to make and use the same, reference being had to the accompanying drawings, making a part of this specification, in which—

Figure 1 is a view of the under side of the hawk.

Figure 2 is a side view.

Similar letters of reference indicate corresponding parts in the two figures.

This invention consists in making the plate of a plasterers' hawk of steel, whereby many advantages are gained, as will be hereinafter more fully described.

In the drawings—

A represents the hawk, which consists of a plate of steel, of proper size and form.

It is secured to an ordinary handle, B, by means of arms C, through the media of rivets, or other fastenings.

The advantages of the steel plate are, that there is no warping or cracking, no roughing of the surface, no rotting, no catching of the trowel in taking off the mortar, and other features which will be readily perceptible to plasterers.

Having thus described my invention,

What I claim as new, and desire to secure by Letters Patent, is—

A plasterers' hawk, having its upper plate, A, made of steel, and attached to the handle by means of the arms C C, as and for the purpose set forth.

Witnesses: THOS. J. McGEARY.

HORACE HARRIS,
NELSON JENKINS.
